Lawrence G. Buckley, Olympia, Wash., assignor
of one-eighth to Barbara Buckley Berken,
Seattle, Wash., one-eighth to Kathleen Buckley
Ogle, Mercer Island, Wash., and one-eighth to
Elizabeth Buckley Martin, Eugene, Oreg.

Application February 28, 1950, Serial No. 8,187

Term of patent 14 years

(Cl. D59—10)

To all whom it may concern:

Be it known that I, Lawrence G. Buckley, a citizen of the United States of America and a resident of Olympia, in the county of Thurston and State of Washington, have invented a new, original, and ornamental Design for an Embossed Decorative Paneling, of which the following is a specification, reference being had to the accompanying drawing, forming part thereof.

The figure is a plan view of an embossed decorative paneling, showing my new design. A design unit is outlined by the rectangle marked on the figure which unit is repeated over the paneling as is indicated by the extensions beyond the unit boundary. The paneling is of conventional thickness throughout.

I claim:

The ornamental design for an embossed deco-

rative paneling, substantially as shown and described.

LAWRENCE G. BUCKLEY.
